Nicholas Muller of New York, U.S.

Letters Patent No. 9060-Dated May 9, 1865.

DES. 2060

Design for a Clock Front.

The schedule referred to in these Letters Patent and making part of the same.

shall when it may occur:

Be it known that Nicholas Muller, of No. 48, 49th Street, in the City, County and State of New York, have invented and produced a new and ornamental Design for a Cast Metal Clock Case Front; and I do hereby declare that the following is a full, clear and exact description thereof, which will enable others skilled in the art to fully understand and practice the same, reference being had to the accompanying drawings forming part of this specification, in which

Figure 1 is a front or face view of my design.

Figures 2 and 3, sections of the same, taken in the lines x, x, y, y, figure 1.

Figure 4, a profile or edge view of the same.

Similar letters of reference indicate like parts.

The lower portion or base of the front of the clock case is provided by curves a-a, a', b-b, b' at the top and bottom and c, c' at its ends, the two lower curves b, b' being ornamented with set figures. The two upper curves a, a', as well as the two end curves c, c' and the lower central curve b' have a plain interior having a rebated or quirk e, at their inner edges, while the central upper curve a', is ornamented with scalloped or leaf figures f.

The centre of this base has an ornamental figure representing two birds g, g, and further, a scroll i, being at each side of this ornamental figure and a pedestal leaf-like ornament k, below it.

The base has two scrolls k, k, at its bottom and ends and the upper portion of the front has a circular opening l, to expose the clock dial. At each side of this opening there is a curve m,

DES. 2060
Decorated by a chain-like device at and above each curve
there is a raised ornament of flowers in and scrolls o. with leaf
ornaments fr.

Claims as new and desires to secure by Letters Patent
The general configuration of the part herein shown
and described to form a new and original design for a cast
metal ice chest front.
